CONTROLLING MEANS FOR GYROSCOPES

William H. Newell, New York, N. Y., assignor to
 Ford Instrument Company, Inc., Long Island
 City, N. Y., a corporation of New York

Application June 15, 1943, Serial No. 490,866

8 Claims. (Cl. 74—5)

In the case of follow-up mechanisms with gyroscopes where power means operate to cause a member to follow the movement of the spin axis of the gyroscope, the power means being under the joint control of the follower member and the gyroscope, it occurs in some constructions that when the speed of precession of the gyroscope exceeds the possible speed of the follower member, the joint control elements operate physically to limit the positional disagreement between the gyroscope and the follower member, and to impose a reactive force upon the gyroscope when the disagreement becomes excessive, which force imposes a couple around the axis in respect to which the disagreement occurs. This couple causes erroneous precession of the gyroscope about its other precession axis. Such irregular performance of a gyroscope is known as tumbling, and it is to means for correcting for such mishap that this invention relates.

The invention is useful and will be explained in association with a gyroscope mounted to have three degrees of freedom, the spin axis of which is capable of being directed at a moving object and to follow the object in space. Forces are applied as couples around the respective precession axes proportional to the respective rates of precession required to cause the spin axis to follow the movement of the object. Such a gyroscope is usually referred to as an angle gyro.

A common use for angle gyros is in directors for anti-aircraft gun fire control mechanism, in which they function to maintain the sighting device on the target. The relative movement of the target has both an elevation and a train component, and the follower member, which may be the support for the sighting device, must therefore have imparted to it a movement that is the resultant of those two components in order to stay on the target. In other words, in anti-aircraft gunnery the line of observation is usually in an inclined plane, but the rate of training is commonly related to the horizontal plane. This is because the training rack about which the sighting device trains is disposed in the horizontal if on land, or in the plane of the deck of a ship if on ship board.

The power motors for the follow-up mechanism are of any suitable type, such as electric or hydraulic, and it is necessary for each to keep up with its component of movement of the gyroscope in order to keep the sighting device directed at the target. As the elevated target, such as an airplane, moves in a direction that involves a train component, the rate of training of the sight

in a horizontal plane in order to follow the precession of the gyroscope in the inclined plane of its spin axis, exceeds the rate of precession, and the ratio between the two rates is the cosine of the angle of elevation. In other words, designating the rate of train in the horizontal as dB_H and the rate of precession of the gyroscope, that is, the rate of train in the inclined plane of sight as dB_N , and the angle of elevation, that is, the angle 10 which the line of sight makes with the horizontal, as A ,

$$\frac{dB_N}{\cos A} = dB_H$$

Therefore at an elevation of 60° the rate of train in the horizontal must be twice the precession rate of the gyroscope in train, and approaches an infinite rate at 90° elevation. At some angle of elevation, therefore, the rate of precession may exceed the capability of the training motor to follow, with the result that the gyroscope will try to get ahead of the follower member. If this causes the contact or other control element that is moved with the gyroscope to jam, there is a reaction upon the gyroscope which causes it to precess in elevation and thus lose the target.

In accordance with this invention means come into action before this point is reached to reduce the precession force that is causing the gyroscope to precess in train so as to limit the precession rate to that at which the motor can train the follower member in the horizontal. Thus it may happen at high elevations that a training rate 30 will be called for in order to follow the target which will exceed the capability of the training motor, with the result that the precession rate of the gyroscope will have to be limited and the sight cannot be moved in train fast enough to keep on the target. However in this way there is avoided the development of a false elevation rate in the movement of the sight, in other words, the gyroscope is not caused to tumble.

Specifically, in the construction shown, there 45 is provided a supplemental motor connected to act upon the mechanism that applies the torque around the elevation axis to effect precession of the gyroscope in train, and when at full motor speed the lag of the follower member in train exceeds a certain amount, the supplemental motor is energized to subtract from the torque causing precession of the gyroscope in train and so reduce the precession rate to that commensurate with the training rate.

To afford the training motor the requisite op-

portunity for speed adjustments, one of the joint control members is made yieldable against a centering spring so as to absorb a limited amount of lag in following, and the arrangement of the control for the supplemental motor is such that the supplemental motor does not become energized until the error exceeds a substantial but predetermined amount.

This safeguard is shown as applied only to the precession rate in train, but it will be obvious that it can be as well applied to limit the elevation rate of precession. However for the use herein contemplated the same problem does not arise in following a target in elevation.

The illustrated embodiment of the invention will now be described and thereafter the invention will be pointed out in claims.

Fig. 1 is a perspective, partly in section, of an apparatus embodying the invention.

Fig. 2 is an end view of the same.

The gyroscope and its associated parts are shown mounted upon a training table 1 arranged to turn in a fixed circular rack 2. Hung on journals 3 in uprights 4 on the table 1 is a cradle 5 which constitutes the follower member and is in effect an open, four sided frame having a top 6, sides 7 and a bottom 8. A training electric motor 9 trains the table 1 and hence the cradle 5, and an elevation electric motor 10 controls the angular disposition of the cradle on its trunnions, that is, its elevation. The train motor 9 is supported by a bracket from one of the uprights 4 and is connected by gears 11, 12, 13, 14 and 15 to the training rack 2. A bracket 16 on the training table supports the bearings for the gears 12, 13 and 14, 15. Thus the turning of the motor 9 will cause the bracket 16 and hence the table to turn in the rack.

The rocking of the cradle on its journals to move it in elevation is similarly effected by the motor 10 through gearing and a fixed rack. As shown, an arcuate rack is fastened to the upright 4 opposite the one on which the motor 9 is mounted, and a pinion 17 on the motor shaft, which turns in a bearing on the adjacent side member 7, engages the teeth on the rack. Thus the turning of the motor will rock the cradle.

A gyroscope 18 is pivoted on horizontal trunnions 19 in a sensitive ring 20 that is pivoted on vertical trunnions 21 in the top and bottom members 6 and 8 of the cradle. The end of the upper trunnion 21 where it projects through the top member 6 of the cradle, has fastened on it an arm 22 that carries a primary contact member 23, cooperative with the contacts of a double secondary contact member 24 pivoted in a bearing on a bracket 25 carried on the top member 6. These primary and secondary contacts are connected through a source of current to the motor 9, as shown, so that the motor is reversely energized by the engagement of the primary contact with one or the other of the double contacts. So the relative movement of the gyroscope and cradle in train energizes the train motor 9 and trains the cradle to follow the gyroscope.

Similarly the relative movement of the gyroscope and cradle in elevation will energize the motor 10. A vertically disposed arm 26 is pivoted on a horizontal axis to the cradle, and at its lower end carries a primary contact 27 that cooperates with the double contacts of a secondary contact member 28, pivotally carried by a bracket arm 29 attached to the bottom member 8. These primary and secondary contacts are connected

through a source of current to the motor 10, as shown, so that the motor is reversely energized by the engagement of the primary contact with one or the other of the secondary contacts. The upper end of the arm 26, at a point above the pivot, is connected to the gyroscope 18 vertically above its spin axis at a point midway between the horizontal trunnions 19, by arms 30 that have a ball-and-socket connection with the gyroscope and with each other. Hence relative movement of the gyroscope about its elevation axis is physically transmitted to the arm 26, and if sufficient will close the contacts 27, 28.

Manual means are shown for adjusting the torques around the respective axes of the gyroscope. The one for adjusting the torque around the vertical axis and so produce precession about the horizontal axis is shown at the bottom and is operated in the form shown by a knob 31. A bell-crank 32 is pivoted on a horizontal slide 33, and has a roller 34 that is urged against the face of a foot-piece 35 of the sensitive ring 20 by a spring 36 connected at one end to the arm of the bell-crank 32 and at the other end to a pin on the slide 33. At either side of the center line the roller applies a torque about the axis 21—21, the moment of which depends upon the displacement of the roller from the center. The knob 31 is operatively connected to the rack 33 by bevel gears 37 and pinion 38 that engages the rack teeth on the slide 33. Therefore in order to cause the spin axis of the gyroscope to precess in elevation, the operator turns the knob 31 and offsets the roller 34 an amount depending upon the desired precession rate.

Similarly the operator turns a knob 39 to cause the gyroscope to precess in train. The spindle of the knob turns in a support 40 on the bottom member 8 and has on its opposite end a pinion 41 that engages with the rack on a vertical slide 42. A bell-crank 43 pivoted on the slide, like bell-crank 32, has a roller on one end and its other end attached to a spring fastened to a pin on the slide. Thus the roller is urged outwardly, and it bears against the edge of the arm 26. When it is opposite the pivot the torque impressed by it is zero, and when it is above and below the pivot it impresses a torque proportional to the displacement from the pivot. This push or pull on the arms 30 applies a couple around the axis 19—19 which causes a precession about the axis 21—21.

As above stated, both the double secondary contacts 24 and 28 are pivotally mounted. Centering springs 44 bias the contact member 24 to a position where the primary contact 23 is midway between the two secondary contacts when the gyroscope and its follower member are in positional agreement in train. Similarly centering springs 45 center the secondary contact member 28 with respect to the primary contact 27. In both instances the centering springs permit the secondary contacts to yield somewhat and absorb some error before the supplemental motor contacts are engaged, as will presently be described. In this way the motors 9 and 10 will have time to get up to full speed before the supplemental motor can act.

Means are provided to limit the accelerations of the motors. Motor 9 is also connected through gears 46, 47 and 48 and the connecting shafts with one side of a differential 49. The other side of the differential is connected to an inertia member 50, while the center of the differential is connected to one of the members of a viscous drag

element 51. The other member of the drag element is fastened on a shaft that bears in the bracket 25 and has a bevel gear 52 on its other end. The gear 52 meshes with bevel gear 53 on the stub shaft that is secured to the secondary contact member 24 and is the pivot that bears in the bracket 25.

Thus it will be seen that the rate of acceleration and deceleration is limited. When the motor 9 starts and before the inertia member 50 gets up to speed, the center of the differential turns and the drag member is operated and tends to turn the contact member 24 on its pivot in a direction to open the contacts and so limit the acceleration of the motor. When the inertia member gets up to speed the drag element is not rotated and the centering springs 44 yield against the pressure of center contact member 24. When the motor 9 slows down the inertia member 50 gets ahead and rotates the drag element in the direction to tend to close the contacts and so prevent the motor from slowing down too fast.

There are similar means to limit the acceleration of motor 10. The armature shaft of motor 10 connects to one side of a differential 54 through pinion 55 on the motor shaft and gear 56 the shaft of which is connected with one side of the differential 54 and bears in adjacent side piece 7 of the cradle and in a bracket arm 57 opposing and like bracket arm 29. The other side of the differential 54 is connected to an inertia member 58, while the center of the differential is connected to one member of a drag element 59. The other member of the drag element is connected to the pivot shaft of the secondary contact member 28.

So long as the speed of precession of the gyroscope is within the speed range of the follow-up motors, the centering springs 44 and 45 will prevent a back pressure from developing on the primary contacts moved by the gyroscope which will cause the gyroscope to tumble. Since, for the reason stated, the inability to follow is likely to occur in train at the higher altitudes, anti-tumbling means are shown only in connection with the means to cause precession in train. Obviously, if desired, similar preventive means may be applied to the means for causing precession in elevation.

In the form shown an anti-tumbler electric motor 60 is employed. This is mounted on an extension of the top 6 of the cradle and has on its shaft a crank 61 the pin of which engages in a slot in the top end of the pivoted arm 26. The motor 60 therefore acts as a torque motor to exert a torque one way or the other upon the arm 26.

Motor 60 is controlled by contacts operated by the relative movement of the gyroscope and cradle in train, and spaced so as to engage only after an appreciable lag has developed, that is, after the centering springs 44 have yielded to the point where further pressure of the center contact 23 will react upon the gyroscope and cause it to tumble.

As shown, two spaced secondary contacts 62 are carried by the follower member 5, and an intermediate primary contact 63 is carried by the sensitive ring 20 of the gyroscope. These contacts are connected to the motor 60 through a source of current, as is shown.

It is now apparent that in order to keep the sight on the target in train, the operator turns the knob 39 to obtain the desired rate of train about the axis 21-21, and that the rate of train

of the table 1 will be more for a given rate of train about the axis 21-21 as the elevation increases. Thus there is a condition approached in which the maximum speed of the motor 9 is insufficient to keep the cradle 5 up with the gyroscope in train. As the lag develops, first the springs 44 yield until contact 63 engages one or the other of contacts 62. This energizes the torque motor 60 and causes it to apply a counter torque on the arm 26 and so diminish the couple around the axis 19-19. Thus the precession rate of the gyroscope in train is brought down to that of the follower member.

It is obvious that the mechanism illustrated and above described represents merely one way in which the principle of the invention may be embodied. Other ways in which the invention may be carried out will readily occur to those skilled in the art.

I claim:

1. Controlling means for gyroscopes comprising, in combination with a supporting member pivoted for movement about two mutually perpendicular axes and a gyroscope mounted in the supporting member for freedom of precession about two mutually perpendicular axes, means for applying controlled precession forces to the gyroscope about each of said precession axes, power means for moving the supporting member about its axes, controls for the power means responsive to the relative angular positions of the gyroscope and its supporting member, and additional means responsive to predetermined relative angular positions for applying a force opposing said precession force.

2. Controlling means for gyroscopes comprising, in combination with a supporting member pivoted for movement about two mutually perpendicular axes and a gyroscope mounted in the supporting member for freedom of precession about two mutually perpendicular axes, means for applying controlled precession forces to the gyroscope about each of said precession axes, a separate power means for moving the supporting member about each of its axes, controls for each power means including two cooperative elements one of which is movable by the gyroscope and the other by the supporting member, and means responsive to predetermined relative movement of said control elements to modify said precession forces.

3. Controlling means for gyroscopes comprising, in combination with a supporting member pivoted for movement about two mutually perpendicular axes and a gyroscope mounted in the supporting member for freedom of precession about two mutually perpendicular axes, precession means for applying controlled precession forces to the gyroscope about each of said precession axes, a separate power means for moving the supporting member about each of its axes, controls for each power means including two contactable elements one of which is movable by the gyroscope and the other by the supporting member, said elements being so mounted that pressure of the one element against the other reacts upon the gyroscope as a precession force, an additional power device operative upon one of said precession means, and a control for the additional power device including two cooperative elements one of which is movable by the gyroscope and the other by the supporting member.

4. Controlling means for gyroscopes comprising, in combination with a supporting member pivoted for movement about two mutually per-

pendicular axes and a gyroscope mounted in the supporting member for freedom of precession about two mutually perpendicular axes, means for applying controlled precession forces to the gyroscope about each of said precession axes, two electric motors operative to move the supporting member about its respective axes, energizing means for each motor including a pair of relatively movable contacts one moved by the gyroscope and the other by the supporting member, one of the contacts being yieldable and having resilient means to bias it to a predetermined relative position, an additional electric motor operative upon one of the means for applying a precession force, and energizing means for the additional motor including a pair of contacts operative respectively by the gyroscope and the supporting member and adapted to engage after engagement of the contacts controlling the motor moving the supporting member.

5. Controlling means for angle gyroscopes comprising, in combination with a supporting member mounted for movement about train and elevation axes and a gyroscope mounted in the supporting member for freedom of precession about train and elevation axes, independent adjustable means for applying a couple around each precession axis, a motor for moving the supporting member about its train axis, a separate motor for moving the supporting member about its elevation axis, means for activating each motor including two cooperative elements one movable by the gyroscope and one by the supporting member, a torque motor operative to modify the couple applied around the elevation axis, and means for activating the torque motor including an element carried by the gyroscope and an element carried by the supporting member, the two elements being cooperative upon relative movement of the gyroscope and supporting member about their train axes.

6. Controlling means for angle gyroscopes comprising, in combination with a supporting member mounted for movement about train and elevation axes and a gyroscope mounted in the supporting member for freedom of precession about train and elevation axes, independent adjustable means for applying a couple around each axis, an electric motor for moving the supporting member about its train axis, a separate electric motor for moving the supporting member about its elevation axis, means for energizing each motor including a pair of relatively movable contacts one movable by the gyroscope and the other by the supporting member, an electric motor having a torque applying connection with the means for applying a couple around the elevation axis of the gyroscope, and means for energizing the torque applying motor including two contact elements one carried by the gyroscope and one by

the supporting member in position to cooperate as a result of relative movement of the gyroscope and supporting member about their train axes.

7. Controlling means for angle gyroscopes comprising, in combination with a supporting member mounted for movement about train and elevation axes and a gyroscope mounted in the supporting member for freedom of precession about train and elevation axes, independent adjustable means for applying a couple around each axis, an electric motor for moving the supporting member about its train axis, a separate electric motor for moving the supporting member about its elevation axis, means for energizing each motor including a pair of relatively movable contacts one movable by the gyroscope and the other by the supporting member, one of the contacts being yieldable and having resilient means to bias it to a predetermined positional relation to the part by which it is moved, an electric motor having a torque applying connection with the means for applying a couple around the elevation axis of the gyroscope, and means for energizing the torque applying motor including two contact elements one carried by the gyroscope and one by the supporting member in position to cooperate as the result of relative movement of the gyroscope and supporting member about their train axes.

8. Controlling means for angle gyroscopes comprising, in combination with a supporting member mounted for movement about train and elevation axes and a gyroscope mounted in the supporting member for freedom of precession about train and elevation axes, independent adjustable means for applying a couple around each axis, an electric motor for moving the supporting member about its train axis, a separate electric motor for moving the supporting member about its elevation axis, means for energizing each motor including a pair of relatively movable contacts one movable by the gyroscope and the other by the supporting member, the contact moved by the supporting member being resiliently mounted on the member so as to yield under pressure of the cooperating contact, an electric motor having a torque applying connection with the means for applying a couple around the elevation axis of the gyroscope, and means for energizing the torque applying motor including two contact elements one carried by the gyroscope and one by the supporting member in position to cooperate as the result of relative movement of the gyroscope and supporting member about their train axes, the last mentioned contacts being mounted so as to engage after the contacts controlling the train motor have engaged and when the yieldable contact is moved from its biased position.
